POWER LAWN MOWER

George A. Wegele, Otis, Kans.

Application June 3, 1953, Serial No. 25,310

Term of patent 14 years

(Cl. D40—1)

To all whom it may concern:

Be it known that I, George A. Wegele, a citizen of the United States, residing at Otis, in the county of Rush, and State of Kansas, have invented a new, original, and ornamental Design for a Power Lawn Mower, of which the following is a specification, reference being had to the accompanying drawing forming a part thereof, wherein:

Figure 1 is a front perspective view of a power lawn mower, showing my new design.

Fig. 2 is a side perspective view thereof; and

Fig. 3 is a rear perspective view of the power lawn mower.

The characteristic features of the design reside in the solid line portions.

I claim:

The ornamental design for a power lawn mower, as shown and described.

GEORGE A. WEGELE.
